CONVERSION OF HYDROCARBON OILS

Kenneth Swartwood, Chicago, Ill., assignor to
 Universal Oil Products Company, Chicago, Ill.,
 a corporation of Delaware

Application November 13, 1936, Serial No. 110,627

5 Claims. (Cl. 196—50)

This application is a continuation in part of my co-pending application, Serial Number 28,803 filed June 28, 1935.

This invention refers to an improved process for the treatment of relatively low-boiling distillates such as motor fuel or motor fuel fractions of poor anti-knock values, naphtha and the like under conversion conditions of elevated temperature and superatmospheric pressure regulated to effect a material improvement in the motor fuel characteristics of the distillate, particularly with respect to anti-knock value, without excessively altering their boiling range.

The invention is particularly advantageous as applied to the treatment of low-boiling distillates, such as above mentioned, which are not adequately reformed in a single pass through the system, in that it provides for the further treatment, under reforming conditions of cracking temperature and atmospheric pressure, of selected intermediate conversion products of the reforming operation to which the charging stock is subjected.

It is now well known that reforming operations of the character above mentioned ordinarily produce only relatively small yields of liquid products of higher boiling characteristics than the charging stock, such as intermediate liquid products corresponding to what is termed reflux condensate in a conventional cracking operation. Furthermore, intermediate products of this general nature, produced in reforming operation, are not ordinarily best adapted to further treatment under the same cracking conditions as the lower boiling charging stock. They may, however, be cracked under independently controlled conditions to produce additional yields of good quality gasoline, but the quantity of such material produced in a reforming operation is ordinarily not sufficient to warrant the use of a separate cracking zone. On the other hand, such materials ordinarily comprise a product which is readily saleable as good quality fuel oil. Therefore, in the present invention, I provide for removing this material from the system, or, when desired, I may utilize the same, in accordance with the provisions of the invention, as a cooling medium for reducing the temperature of the high heated products from either or both cracking zones of the system, in order to prevent excessive continued conversion of said heated products.

In operations of the character above outlined it is ordinarily necessary, in order to produce a finished motor fuel of the desired characteris-

tics, to subject the light distillate product of the reforming operation to stabilization to free the same of undesirable light ends and dissolved gases whereby to lower the vapor pressure of the final product to the desired degree and, in order to insure recovery of the maximum yield of motor fuel, it is particularly desirable, in an operation of this character, to subject the gaseous products of the process to absorption for the recovery of their desirable components within the boiling range of the motor fuel product.

As a feature of the invention, the absorber oil utilized for recovering said desirable high-boiling components of the gases comprises the selected relatively low-boiling intermediate liquid products of the process, above referred to. This absorber oil includes high-boiling gasoline fractions produced by the reforming operation to which the charging stock is subjected and which require further treatment to improve their anti-knock value. It may also include, when desired, higher boiling materials, such as naphtha, kerosene, kerosene distillate and the like, which in a conventional cracking or reforming operation, would be included in and comprise the low boiling fractions of the total reflux condensate.

As another feature of the invention, the enriched absorber oil resulting from the last described step of the process is preferably cracked, under independently controlled cracking conditions, in a separate heating coil of the system, or, as an alternative but non-equivalent method of operation, a regulated portion or all of the enriched absorber oil may be returned to further treatment in the same cracking coil to which the charging stock is supplied. Although no attempt will be made here to explain the mechanism of the reactions involved in this step of the process, I have found that, when these selected intermediate liquid conversion products are subjected to further cracking in the presence of the unsaturated relatively high boiling components of the gases, such as propylene and butenes, for example, the yield of good quality gasoline may be materially increased. This may be due to polymerization of the unsaturated gases under the temperature and pressure conditions employed in said separate heating zone, or to some other reaction between the unsaturated gases and compounds contained in the oil with which they are commingled in said separate heating coil, or it may be due in part to both.

It will be apparent from the foregoing that the invention combines the steps of selective cracking and reforming stabilization and ab-

sorption in a cooperative and advantageous manner in a single unified system wherein light distillates, such as gasoline, or gasoline fractions of poor antiknock value, naphtha and the like, 5 may be treated to produce high yields of good antiknock gasoline with minor yields of higher boiling liquid products and relatively light gases.

One specific embodiment of the invention comprises subjecting hydrocarbon oil charging stock, 10 such as low boiling distillate containing an appreciable quantity of materials within the boiling range of gasoline, but of poor antiknock value, to reforming conditions of cracking temperature and substantial superatmospheric pressure in a heating coil, removing from the resulting products, 15 non-vaporous high-boiling components such as heavy polymers and residual liquids, separating the vaporous components of said products, by fractionation, into selected relatively low-boiling and higher boiling intermediate products and 20 fractionated vapors of the desired end boiling point and antiknock value, removing said high-boiling intermediate liquid products from the system, subjecting said fractionated vapors to 25 condensation, recovering and separating the resulting distillate and uncondensed gases, subjecting said distillate to stabilization for the purpose of reducing its vapor pressure, recovering the stabilized distillate as the final gasoline product 30 of the process, subjecting the gaseous products, including those evolved from the distillate by stabilization, to absorption for the removal therefrom of a desirable high-boiling components by intimately commingling said gases with said selected low-boiling fractions of the intermediate 35 liquid conversion products, subjecting the resulting enriched absorber oil to further treatment within the system under cracking conditions of elevated temperature and substantial super-atmospheric pressure and subjecting resulting products to the aforementioned steps of separation, fractionation, etc.

The accompanying diagrammatic drawing illustrates one specific form of apparatus in which 40 the process of the invention may be accomplished. Referring to the drawing, hydrocarbon oil charging stock for the process, comprising a relatively low-boiling distillate containing a substantial proportion of materials within the boiling range 45 of motor fuel but of poor antiknock value, such as straight-run or cracked gasoline, naphtha or the like, is supplied through line 1 and valve 2 to pump 3 by means of which it is fed through line 4 and valve 5 into heating coil 6. The charging stock may, of course, be preheated in any well known manner, not illustrated in the drawing, prior to its introduction into the heating coil.

A furnace 7 of any suitable form supplies the 50 required heat to the oil passing through heating coil 6 to subject it to the desired conversion conditions of elevated temperature, preferably at a substantial superatmospheric pressure, and, although the heating coil is illustrated in a conventional manner in the drawing, it is preferably of such form, several modifications of which are now well known, that the oil may be brought quickly to the desired conversion temperature and then maintained at or near the maximum temperature attained for a predetermined time.

The stream of hot conversion products is discharged from heating coil 6 through line 8 and valve 9 into column 10 and, preferably, in order to definitely control the conversion time as well 70 as the temperature and pressure conditions to

which the oil is subjected, provision is made for cooling the stream of hot conversion products discharged from the heating coil sufficiently to prevent any substantial further conversion thereof. An appreciable reduction in the pressure 5 imposed upon the oil as it passes through valve 9 serves to effect appreciable cooling of the conversion products and assists their vaporization and fractionation in column 10. Provision is also made, in the case here illustrated, for effecting any desired degree of additional cooling 10 of the conversion products by directly commingling a suitable cooling liquid with the stream of products passing through line 1, by introducing the cooling medium thereto through 15 line 11 and valve 12. The liquid utilized for this purpose may comprise any desired oil, preferably of relatively low-boiling characteristics, which will not contaminate the conversion products, and may include, for example, a regulated portion 20 of the distillate collected, as will be later more fully described, in receiver 30 or regulated quantities of the intermediate liquid conversion products of the process recovered from column 10, as will be later more fully described. 25

Column 10 comprises, in the particular case here illustrated, a lower portion 13, comprising a vaporizing and separating chamber, wherein non-vaporous residual liquid conversion products, heavy polymerization products and the like are separated from the vapors, and an upper portion or fractionating column 14 wherein two selected fractions of the intermediate products, comprising high-boiling components of the vapors, are condensed and separated from the 30 overhead vaporous product, the latter comprising materials of the desired end-boiling point and antiknock value within the range of gasoline and the normally gaseous products produced by the cracking operation. 40

Residual liquids, including high-boiling polymerization products and the like, may be removed from the lower portion 13 of column 10 through line 15 and valve 16 to cooling and storage or elsewhere, as desired. 45

The selected high boiling fractions of the intermediate liquid conversion products condensed in fractionator 14 are, preferably, substantially devoid of materials within the boiling range of gasoline and comprise the intermediate liquid 50 products which are not particularly suitable for further cracking under high temperature and pressure conditions. This material may be allowed to accumulate in the lower portion of fractionator 14, above a suitable partition 17 which separates the upper and lower portions of column 10, and it may be removed therefrom through line 22 and valve 23 to cooling and storage or to any desired further treatment. It is also within the scope of the invention to utilize regular quantities of this material, preferably after it has been cooled to the desired degree, as a cooling medium in line 8 by supplying the same thereto through line 11 and valve 12, by well known means not illustrated, and/or, when a separate heating coil such as indicated at 68 is employed, this material may be utilized as a cooling medium in discharge line 70 from this zone by supplying the same thereto in regulated quantities through line 72 and valve 13. It is also within the scope 60 of the invention to blend high-boiling oils collected in the lower portion by fractionator 14 with the heavy residual liquid products removed from chamber 13, as previously described, through line 15 and valve 16 and, although means for 65

accomplishing this are not illustrated in the drawing, these materials may be blended either within or external to chamber 13.

Selected low-boiling fractions of the intermediate liquid conversion products condensed in fractionator 14 may be withdrawn therefrom at any suitable intermediate point or plurality of points therein and, in the case here illustrated, are directed through line 20 and valve 24 to pump 21, whereby they may be supplied to further treatment within the system, as will be later described.

Fractionated vapors of the desired end-boiling point, comprising the final motor fuel product of the process and normally gaseous products, are directed from the upper portion of fractionator 14 through line 25 and valve 26 to condensation and cooling in condenser 27. The resulting distillate and gas passes through line 28 and valve 29 to collection and separation in receiver 30. Uncondensed gases may be released from receiver 30 through line 31 and valve 32 and are directed, in the case here illustrated, through valve 33 in line 31 to absorber 34, wherein they are subjected to absorption together with the other process gases, as will be later more fully described. Distillate is withdrawn from receiver 30 through line 35 and valve 36 to pump 37 by means of which it is supplied through line 38 and valve 39 to stabilization in stabilizer 40.

A regulated portion of the distillate collected in receiver 30 may, when desired, be recirculated by well known means, not shown in the drawing, to the upper portion of fractionator 14 to serve as a cooling and refluxing medium in this zone for assisting fractionation of the vapors and to maintain the desired vapor outlet temperature from the fractionator.

The distillate supplied to stabilizer 40 is reboiled and subjected to partial vaporization in any suitable manner such as, for example, by means of a heating coil 41 located in the lower portion of the stabilizer, through which any suitable heating medium such as steam, hot oil or the like may be passed. The reboiled and stabilized distillate is withdrawn from the lower portion of column 40 through line 42 and valve 43 to cooling and storage or elsewhere, as desired. The components of the distillate vaporized in stabilizer 40 are subjected to fractionation in this zone, whereby the undesirable low-boiling components of the distillate and entrained gases are liberated therefrom so as to reduce the vapor pressure of the final motor fuel product.

The low-boiling materials liberated in stabilizer 40 are withdrawn from the upper portion of this zone through line 44 and valve 45 and are directed through valve 33 in line 31 to absorber 34. A regulated portion of the low-boiling materials from stabilizer 40 may be diverted from line 31 through line 46 and valve 47 to a condenser and cooler 48, of any suitable form capable of liquefying the high-boiling components of the normally gaseous materials, and the resulting distillate and gas passes through line 49 and 50 to collection and separation in receiver 51. The distillate thus formed may be recirculated in regulated quantities, by means of line 52, valve 53, pump 54, line 55 and valve 56, to the upper portion of stabilizer 40 to serve as a refluxing and cooling medium in this zone, in order to assist fractionation of the vaporous products in the stabilizer and maintain the desired outlet temperature from this zone.

The uncondensed gases from receiver 51 may

be directed, either alone or together with any excess quantity of distillate collected in this receiver and not required as reflux medium in stabilizer 40, through line 57, valve 58 and line 31 to absorber 34. Provision is also made for directing regular quantities of the distillate collected in receiver 51, comprising the quantity of such material not required as a reflux medium in stabilizer 40, from line 55, through line 80 and valve 81 into line 66 wherefrom it may be returned through line 74 and valve 75 to further treatment in heating coil 6, together with the charging stock, or it may be directed, all or in part, through valve 67 in line 66 to further treatment in heating coil 68, together with said selected low-boiling intermediate liquid products from fractionator 14.

The intermediate liquid conversion products supplied, as previously described, from fractionator 14 to pump 21 may be supplied, all or in part, through line 59 and valve 60 into the upper portion of absorber 34, wherein they serve as an absorber oil to remove from the gases supplied to this zone desirable relatively high-boiling components, including propylene, butenes and the corresponding saturated compounds. The relatively lean gases remaining unabsorbed in column 34 are released from the upper portion of this zone through line 61 and valve 62 to storage or elsewhere, as desired. The enriched absorber oil is withdrawn from the lower portion of column 34 through line 63 and valve 64 to pump 65, by means of which it is fed through line 66 and may be directed through valve 67 in this line to further conversion in heating coil 68, or it may be directed through line 74, valve 75 and line 4 to conversion in heating coil 6, together with the charging stock.

When desired, a regulated portion or all of the selected relatively low boiling fractions supplied to pump 21, as previously described, may be directed from line 59 to further cracking in either heating coil 6 or heating coil 68, by means of the respective lines 78 and 76, controlled respectively by valves 79 and 77.

Heating coil 68 is located in a suitable form of furnace 69 by means of which, when this separate heating coil is employed, sufficient heat is supplied to the oil passing through this zone to subject it to the desired conversion temperature, preferably at a substantial superatmospheric pressure. Like heating coil 6 and furnace 7, heating coil 68 and furnace 69 are preferably of such form that the oil supplied thereto may be maintained therein at a temperature near the maximum attained for a predetermined time, although the heating coil is illustrated in the drawing in a conventional manner.

The heated products from heating coil 69 are directed through line 70 and valve 71 into the vaporizing and separating section 13 of column 10, preferably being cooled sufficiently during their passage through line 70 to prevent any excessive further conversion thereof. Valve 71 in line 70 permits a substantial reduction in pressure between heating coil 68 and chamber 13, whereby appreciable cooling of the hot conversion products from heating coil 68 is accomplished and whereby their vaporization is assisted in chamber 13 and, in addition, line 72 and valve 73, communicating with line 70, are provided, whereby a suitable cooling medium may be commingled with the stream of conversion products passing from heating coil 68 to chamber 13, in order to further reduce their tempera- 75

ture to the desired degree. Examples of the materials which may be employed as cooling liquid in line 70 have already been given in connection with the cooling of the conversion products from heating coil 6.

When the intermediate conversion products utilized as absorber oil in absorber 34 and thereafter subjected to further conversion include a substantial proportion of intermediate conversion products boiling above the range of the charging stock, this material is preferably subjected to conversion in heating coil 68, separate from the charging stock. The separate heating coil 68 may be employed for treatment of the intermediate conversion products in any case, when so desired. However, when the enriched absorber oil does not have an appreciably higher end-boiling point than the charging stock, it is normally subjected to conversion in heating coil 6, together with the charging stock.

The preferred range of operating conditions which may be employed to accomplish the objects of the present invention, in an apparatus such as illustrated and above described, may be approximately as follows: The maximum temperature to which the charging stock is subjected in the heating coil to which it is supplied may range, for example, from 950 to 1050° F. and it is preferably maintained for a predetermined time at a temperature within approximately 50° or less of the maximum attained. It is then cooled to a temperature of the order of 700 to 800° F. or less, and introduced into the vaporizing and separating chamber. A substantial superatmospheric pressure is preferably employed in the heating coil ranging, for example, as measured at the outlet, from 300 to 1000 pounds, or more, per square inch. The vaporizing and separating chamber is preferably operated at a substantially reduced pressure relative to that employed in the heating coil ranging, for example, from 150 pounds, or thereabouts, per square inch down to substantially atmospheric pressure. The pressure employed in the fractionating, condensing and collecting portions of the system may be substantially the same or lower than the pressure employed in the vaporizing and separating chamber. The stabilizing column may be operated at any desired pressure ranging from 250 pounds, or more, per square inch, down to substantially atmospheric pressure, and any desired pressure within substantially this same range may be employed in the absorption column.

When a separate heating coil is employed for conversion of the enriched absorber oil, the range of conditions which may be employed in this zone are substantially the same as those which may be employed in the other heating coil but the conditions employed in the two heating coils are independently controlled and, normally, different conditions are utilized in the two heating coils.

As a specific example of the operation of the process of the invention, the charging stock, which comprises gasoline of exceptionally poor anti-knock value, obtained from Michigan crude, is subjected to a conversion temperature, measured at the outlet of the heating coil to which it is supplied, of approximately 980° F. at a superatmospheric pressure of about 800 pounds per square inch and, after being cooled to a temperature of approximately 750° F. by pressure reduction and by commingling therewith regulated quantities of the high boiling reflux condensate,

after cooling the latter, is introduced into the vaporizing and fractionating column which is operated at a superatmospheric pressure of approximately 60 pounds per square inch. This pressure is substantially equalized in the condensing and collecting portions of the system, the stabilizing column is operated at a superatmospheric pressure of approximately 175 pounds per square inch and a superatmospheric pressure of approximately 60 pounds per square inch is maintained in the absorber. A gasoline product of approximately 400° F. end-boiling point is removed, in vaporous state, together with the gaseous products of the process, as the over-head stream from the fractionator, but fractionation is so controlled that the selected intermediate liquid products removed as a side-stream from the fractionator include some materials boiling within the range as the over-head product as well as somewhat higher boiling materials. This product, which has a boiling range of approximately 270° to 550° F., is supplied to the absorber and, after being enriched by absorbing high boiling components of the process gases, it is subjected in a separate heating coil to an outlet conversion temperature of approximately 970° F. at a superatmospheric pressure of about 750 pounds per square inch. The stream of conversion products from this zone is also cooled to a temperature of approximately 750° F. and then introduced into the vaporizing chamber. High-boiling components of the intermediate liquid products condensed in the fractionator are recovered as a final product of the process, as is also residual liquid from the vaporizing chamber. The above described operation will produce, per barrel of charging stock, approximately 78 per cent of 400° F. end-point gasoline having an octane number of 70 or better by the motor method and approximately 800 cubic feet of relatively lean gas, the remainder being chargeable principally to heavy liquid products.

I claim as my invention:

1. A process for the reforming of hydrocarbon distillates of low-boiling characteristics, which contain an appreciable quantity of fractions of low antiknock value boiling within the range of gasoline, for the purpose of producing a gasoline of materially improved antiknock value, which comprises subjecting the distillate in a heating zone to cracking conditions adequate to enhance its antiknock value, separating the resulting products into vaporous and non-vaporous components in a separating zone, subjecting said vaporous components to fractional condensation to separate the same into a heavy reflux condensate substantially devoid of gasoline, a lighter reflux condensate containing high-boiling gasoline fractions, a distillate product containing substantially all of the low-boiling gasoline fractions in said vaporous products and a normally gaseous product, recovering said distillate product, contacting at least a portion of said gaseous product with said lighter reflux condensate to absorb high-boiling components including propylene and butenes of the former in the latter, subjecting resultant enriched lighter reflux condensate to cracking conditions of temperature, pressure and time controlled independently of those employed for the distillate charging stock and adequate to convert the same into high yields of good antiknock gasoline, and subjecting the vaporous products of the last mentioned cracking step to said fractional condensation, to-

gether with the vaporous products of the first mentioned cracking step.

2. A process for the reforming of hydrocarbon distillates of low-boiling characteristics, which contain an appreciable quantity of fractions of low antiknock value boiling within the range of gasoline, for the purpose of producing a gasoline of materially improved antiknock value, which comprises subjecting the distillate in a heating zone to cracking conditions adequate to enhance its antiknock value, separating the resulting products into vaporous and non-vaporous components in a separating zone, subjecting said vaporous components to fractional condensation to separate the same into a heavy reflux condensate substantially devoid of gasoline, a lighter reflux condensate containing high-boiling gasoline fractions, a distillate product containing substantially all of the low-boiling gasoline fractions in said vaporous products and a normally gaseous product, subjecting the distillate to stabilization for the purpose of reducing its vapor-pressure by releasing additional quantities of normally gaseous products therefrom, recovering the stabilized distillate, absorbing at least a portion of the last-named gaseous products including propylene and butenes in said lighter reflux condensate, heating the resultant enriched lighter reflux condensate under cracking conditions of temperature, pressure and time controlled independently of those employed for the distillate charging stock and adequate to produce high yields of good antiknock gasoline therefrom, and subjecting the vaporous products of the last mentioned cracking step to said fractional condensation, together with said vaporous products of the first mentioned cracking step.

3. A process such as defined in claim 2 wherein at least a portion of the first mentioned normally gaseous products are subjected to absorption, together with said normally gaseous products from the stabilization step.

4. A conversion process which comprises subjecting a light paraffinic oil of the character of gasoline and naphtha to reforming conditions of temperature and pressure in a conversion zone and fractionating the resultant vapors and gases to condense and separate fractions thereof heav-

er than gasoline, further fractionating the uncondensed gasoline vapors and gases to separate therefrom an intermediate condensate containing heavy gasoline fractions of inferior antiknock value, subjecting the remaining light gasoline vapors and gases to final condensation under sufficient pressure to liquefy a substantial portion of the gases with the light gasoline vapors, stabilizing the resultant final condensate to remove normally gaseous hydrocarbons therefrom, combining at least a portion of said gaseous hydrocarbons, including polymerizable olefins, with a substantial portion, at least, of said intermediate condensate, subjecting the resultant mixture in a second conversion zone to independently controlled conditions of temperature and pressure adequate to reform the intermediate condensate and polymerize normally gaseous olefins, and recovering from the resultant products a distillate boiling within the gasoline range.

5. A conversion process which comprises subjecting a light paraffinic oil of the character of gasoline and naphtha to reforming conditions of temperature and pressure in a conversion zone and fractionating the resultant vapors and gases to condense and separate fractions thereof heavier than gasoline, further fractionating the uncondensed gasoline vapors and gases to separate therefrom an intermediate condensate containing heavy gasoline fractions of inferior antiknock value, subjecting the remaining light gasoline vapors and gases to final condensation under sufficient pressure to liquefy a substantial portion of the gases with the light gasoline vapors, stabilizing the resultant final condensate to remove normally gaseous hydrocarbons therefrom, scrubbing the latter with at least a portion of said intermediate condensate to absorb polymerizable gaseous olefins in the condensate, subjecting the thus enriched intermediate condensate in a second conversion zone to independently controlled conditions of temperature and pressure adequate to reform the intermediate condensate and polymerize normally gaseous olefins, and recovering from the resultant products a distillate boiling within the gasoline range.

KENNETH SWARTWOOD.
